UNITED STATES PATENT OFFICE.

ARTHUR H. ADAMS, OF SPARKILL, NEW YORK, ASSIGNOR TO WESTERN ELECTRIC COMPANY, OF NEW YORK, N. Y., A CORPORATION OF ILLINOIS.

IMPULSE-TRANSMITTING MECHANISM.

1,164,626.

Specification of Letters Patent.

Patented Dec. 21, 1915.

Application filed November 30, 1914. Serial No. 874,683.

To all whom it may concern:

Be it known that I, ARTHUR H. ADAMS, a citizen of the United States, residing at Sparkill, in the county of Rockland and State of New York, have invented certain new and useful Improvements in Impulse-Transmitting Mechanisms, of which the following is a full, clear, concise, and exact description.

10 This invention relates to impulse transmitting mechanism, for use particularly in substations for automatic exchanges, and has for its object to provide a new and improved device of this character, of few and simple parts, in which the possibilities of confusing the receiving mechanism by a forced operation of the transmitting device are eliminated by the provision of means for locking the setting means against operation during 20 the operation of sending out impulses.

In a device embodying the features of this invention there is a setting device operable in forward and backward directions, an interrupter also operable in forward and backward directions but effective only in its backward movement to send out impulses, and connections between said setting device and said interrupter for causing the operation of said interrupter only after said setting device has returned to normal position, and for locking said setting device in normal position until said interrupter has completed its operation.

In the drawings illustrating this invention—Figure 1 is a perspective view of the impulse transmitting device with a portion of the mechanism cut away; Fig. 2 is a sectional view taken on the line 2—2 of Fig. 3; Fig. 3 is a sectional view taken on the line 3—3 of Fig. 2; Fig. 4 is a sectional view taken on the line 4—4 of Fig. 3; and Figs. 5 and 6 are views of details of the impulse sending mechanism.

The impulse transmitter comprises a dial 45 plate 7 mounted in front of which by means of a shaft 8, is a finger hole plate 9. The dial plate 7 forms the front wall of a cylindrical inclosing case 10 for housing the mechanism used in transmitting impulses. 50 The shaft 8 has its inner end recessed to accommodate a second shaft 11, the latter of which is mounted axially of the casing 10 and functions as a supporting means for rotatably mounting the various elements comprising the impulse sending mechanism.

The finger plate 9, is separated from the dial plate 7 by means of a bearing 12, which functions to provide a space between the dial and finger plate. Within the casing 10 and adjacent the dial plate 7 is a coil spring 60 13 which is attached to the shaft 8 and adapted to supply the motive power for operating the impulse sending mechanism when it is wound up by rotating the finger plate 9 in a clockwise direction, and afterward released by the operator. Extending from the shaft 8 is a lever arm 14, the free end of which has a reduced portion forming an extension finger. Immediately back of the reduced portion of the lever arm 14 and 65 projecting a short distance on both sides thereof, is mounted a pin 15 which serves as a pivot for a spring pressed pawl 16 and as a stop for locking the finger plate 9. Next to the lever arm 14 and carried by a bearing 17 journaled upon the shaft 11 is a ratchet wheel 18. The pawl 16 is positioned to be in operative relation with the ratchet wheel 18, so that when the pawl is moved in a counter-clockwise direction, the ratchet 70 wheel is advanced thereby. Adjacent the ratchet wheel 18 and attached to the bearing 17 is a second coil spring 19. It may be mentioned here that the strength of the spring 19 is considerably less than that of 80 spring 13, which permits the former spring to wind the latter spring in a manner hereinafter explained. The outer or free end of the springs 13 and 19 are fastened to any suitable support or retaining member 20 85 which is secured to the casing 10. Mounted upon a bearing 21 which may be integral with or connected to the bearing 17 is an impulse wheel 22 having a corresponding number of teeth as there are digits or designation characters made upon the dial plate 7.

Pivotedly mounted to the rear wall 23 of the inclosing case 10 and in operative relation with the impulse wheel 22 and contact spring members 24, is a bell crank lever 100 25. The long arm of the lever 25 carries a roller which engages the teeth of the impulse wheel 22 when it is rotated. A spring 31 attached to a projection on the bell crank lever 25 and having its opposite end anchored by a post 32, functions as a means for normally keeping the contact lever 25 out of engagement with contact spring members.

Mounted intermediate the coil spring 19 110

and the impulse wheel 22 is a large gear wheel 33 which is adapted to mesh with a pinion 34. The pinion 34 is secured to a shaft 35 carried by a bracket 36 that is 5 suitably fastened by means of screws 37 to the rear wall 23 of the case 10. Mounted upon the shaft 35 is a worm gear 39 adapted to mesh with a worm 40 formed upon a shaft 38 carrying a governor mechanism. The governor mechanism (illustrated best by Fig. 4) comprises the main drive shaft 38 adjustably mounted by means of screws 42, 42 which are carried by supports 43, 43. Upon one end of the shaft 38 10 is placed a governor wheel 44 having associated with it a pair of governor springs 45. The governor springs 45 are confined in a cup-shaped member 46 having two bearing surfaces of different diameters. The object 15 of having the member 46 this form, is to provide different speeds for the governor mechanism so that the impulse wheel 22 may be rotated faster in one instance than is expedient in another, as will be fully set 20 forth hereinafter.

Attached to a supporting bracket 47 which is secured to the rear wall 23 is a latch member 48, which is secured to a shaft 49 carried by said bracket 47. An arm 50 25 of the latch member 48 engages a pin 51 carried by the ratchet wheel 18, under certain conditions. Another arm 52 of said member 48 engages the pin 15 under other conditions. An extension member 53 fastened 30 to the opposite end of the shaft 49, under the tension of a spring 54, tends to rotate the shaft 49 in an upward direction, thereby keeping the arm 50 of the latch member 48 normally engaged with the pin 51, and when 35 the ratchet wheel 18 is rotated, said extension comes to rest against the stop post 32. To limit the movement of the ratchet wheel 18 when rotating, in a clockwise direction, an extension member 55 carried by said 40 wheel 18, is arranged to strike against a normal post member 56. The normal post 56 also functions to arrest the movement of the lever arm 14 in a counter-clockwise direction, when a pin 27, mounted upon an extending portion of the pawl 16, engages the 45 lower side of said post. This feature permits the finger hole plate 9 to be rotated only in a clockwise direction from normal position. It will be noted that the opposite 50 end of the pin 27 is adapted to engage with the finger shaped portion of the lever arm 14, thereby limiting the backward movement of the pawl 16, but allowing sufficient movement of said pawl so that it may be 55 freed from engagement with the ratchet wheel 18, which fact permits said ratchet wheel to be rotated independent of said pawl under certain conditions.

The operation of the mechanism comprising 60 the impulse transmitter is as follows:

The operator places his finger in the hole in front of the digit forming a part of the number he wishes to call, and turns the finger hole plate 7 in a clockwise direction until his finger strikes the finger stop 26. This 70 operation causes all the elements carried by the shaft 8 to be rotated in a clockwise direction, thus effecting the winding of the coil spring 13, and the rotation of the lever arm 14 and pawl 16 carried thereby. When 75 the operator removes his finger, the energy now stored up in the coil spring 13, rotates the shaft 8 in a counter-clockwise direction. The pawl 16 under the tension of its spring 80 engages one of the teeth of the ratchet wheel 18, thereby causing all of the mechanism mounted upon the shafts 17 and 21 to be moved in a counter-clockwise direction under the influence of the coil spring 13. This movement continues until the pin 27 engages 85 with the normal post 56, which arrests the extension arm 14 and at the same time causes the pawl 16 to become disengaged from the ratchet wheel 18.

It will be noted that when the ratchet 90 wheel 18 was rotated as described above, the arm 50 of the ratchet lever 48 was freed from engagement with the pin 51, and under the tension of the spring 54 the lever 48 was given a slight rotary movement until 95 the stop arm 53 engaged the stop pin 32. This operation permitted the hook formed upon the extremity of the lever 52, to engage with the pin 15 when the lever arm 14 came to rest. By virtue of this arrangement it is now impossible to rotate the finger plate 9 until the ratchet wheel 18 has 100 been returned to normal position, thereby effecting the disengagement of the hook on the lever arm 48 with the pin 15. This feature prevents the sending of impulses until all of the apparatus has returned to normal position, thus eliminating the possibility of confusion of impulses which might otherwise result.

Upon the disengagement of the pawl 16 from the ratchet wheel 18, the energy now stored in the coil spring 19, rotates the elements carried by the shafts 17 and 21 in a clockwise direction. The rotation of the impulse wheel 22 in this direction causes the teeth thereof to engage the long arm of the bell crank lever 25, and as the teeth pass under the roller carried by said arm, the lever 25 is moved in a downward direction, thereby causing the contact springs 24 to be reopened. As each of the various teeth pass on they disengage the roller of the lever arm permitting the bell crank lever 25 to return to normal position, thus effecting the closure 115 of the contact springs 24. This intermittent closing and opening of the contact springs 24 produce impulses which may be transmitted over a circuit desired to be effected. It will be apparent that when 120 125 130

the impulse wheel 22 was rotated in a counter clockwise direction, the bell crank lever 25 was actuated, but in a reverse manner which prevented the opening of contact 5 24. It is, therefore, only possible to transmit impulses when the impulse wheel 22 is rotated in a given direction.

Returning to the operation of the governing mechanism, it will be seen that said mechanism was first operated when the shaft 21 was rotated in a counter clockwise direction. In this operation the governor springs 45 carried on the governor shaft 38, due to the direction of the rotation and a corresponding longitudinal movement of the shaft 38, engaged the greater diameter of the cupped member 46. Because of the reduced friction between the governor springs and the bearing surface now engaged thereby, the shaft 38 was permitted to rotate at a higher speed than when the shaft is rotating in the opposite direction. When the impulse wheel moves in a clockwise direction, the direction of rotation and longitudinal movement of the governor shaft 38 is reversed, and the governor springs 45 then engage the smaller bearing surface of the cupped member 46 which considerably reduces the movement of the impulse wheel 22 and the mechanism rotated in synchronism therewith. It will thus be seen that when the impulse wheel 22 is rotated in a counter clockwise direction, it may be rotated at a greater speed than when turning in a clockwise direction. This feature provides a means for rapidly setting the impulse sending mechanism, and a slower and more uniform speed for transmitting the impulses.

40 From the above description it will be apparent that the features of this invention are to provide an impulse transmitting device which embodies means whereby it is possible to control the speed at which impulses may be transmitted, and also prevent the transmission of succeeding impulses until the preceding impulses have been sent, and the transmitting mechanism returned to normal position.

45 50 What is claimed is:

1. In an impulse transmitting device, an interrupter movable in forward and backward directions, contact springs operated by said interrupter in one direction of movement to send out current impulses, an actuating means movable in forward and backward directions, connecting means between

said interrupter and said actuating means for causing the operation of said interrupter after said actuating means has returned to normal position, and means for locking said actuating means against movement during the movement of said interrupter to send out impulses.

2. In an impulse transmitting device, an interrupter movable in forward and backward directions, contact springs operated by said interrupter in one direction of movement to send out current impulses, setting mechanism movable in forward and backward directions, connecting means between said setting means and said interrupter for moving said interrupter in the same relative direction to the movement of said setting means, means for moving said interrupter in a reverse direction, and means under the joint control of said setting and connecting means for locking said setting mechanism in normal position during the impulse sending movement of said interrupter.

3. In an impulse transmitting device, a finger dial rotatable in forward and backward directions, a shaft upon which said finger dial is carried, a pivotal pawl, supporting means for said pawl carried by said shaft, a second shaft rotatable independently of said first-mentioned shaft, a disk carried thereby having notches in its periphery adapted to be engaged by said pawl in a given movement of said finger dial to rotate said second-mentioned shaft, means for disengaging said pawl from said disk when said finger dial has reached normal position, means for rotating said second-mentioned shaft in a direction opposite to that in which it was rotated by the movement of the finger dial, circuit-interrupting springs operated in the last movement of said shaft to send out current impulses, a pivotally supported latch adapted to engage said pawl supporting means to prevent the rotation of said finger dial during the sending out of impulses, and means carried by said notched disk for disengaging the said latch from said pawl supporting means at the end of the impulse sending operation of said interrupter.

In witness whereof, I hereunto subscribe my name this 28th day of November, A. D. 1914.

ARTHUR H. ADAMS.
